Inventor:

Albert C. Fischer,

By Ballard Moore atty

UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

COMBINED EXPANSION AND CONTRACTION JOINT

Application filed May 19, 1927. Serial No. 192,710.

Heretofore, in concrete paving where contraction was to be provided for it has been the practice to insert a piece of metal longitudinally or transversely below the surface, so that when the concrete block or slab is fully poured and completed the contraction joint is not visible at the surface. After the concrete sets and contracts the function of these pieces of metal is to cause a very fine crevice to develop thru the entire slab, so that it becomes visible on the surface, and functioning in this way it is styled a contraction joint.

Further development in this style of allowing for expansion and contraction in concrete pavements can be made in which a wedge or angular formation is provided, so that the projections developing in one concrete slab, by reason of filling in these projections in the contraction joint, penetrate the other slab so that resistance is caused to any lifting action on the part of the concrete slab. Some of these formations have been angular and some half hexagonal in shape, 25 with straight flanges extending on either side in a vertical position when placed. These contraction joints, while causing the crevice to form along a straight line across the concrete slab or in the surface above which the contraction point is inserted, do not prevent the ingress of water, street acids and the like, which would tend to hastily corrode the metal contraction joint, and also enter the subsoil underneath the slab, keeping the subsoil in the crevice in a constantly wet damp condition.

My invention provides for an improved contraction joint which has many advantages, and which also provides for the waterproofing of the contraction joint automatically, as well as allowing a better pivot motion on the projection anchor in the adjoining slab. This is caused by the insertion of a bituminous slab of varying thickness, 40 pending upon the requirements. The contraction joint flanges are embedded in the bituminous slab on either side of the projecting center. This not only tends to preserve the metal flanges but also has a tendency to 45 protect the projection, because in expanding

in warm weather some of this bituminous material will find its way along the surface of the uncovered metal.

A metal contraction joint may advantageously be coated with paint or bituminous material, in addition to the projecting slabs of bituminous material acting both as expansion and contraction joints.

Expansion joints have usually been placed so that the upper edge of the joint was visible 60 on the surface of the pavement, and in many cases was allowed to project above the surface, so that the traffic would form a sort of mushroom top over the crevice.

It can be readily understood that the purpose of this invention is to totally submerge both the contraction and expansion parts of this joint beneath the surface, so that when the concrete is finished and poured it will not be visible on the surface but will accomplish 70 the same function, in causing a crevice to form across the surface, due to contraction. It will further function by waterproofing this crevice from within, and upon expansion of the bituminous material, and also the 75 pavement, it will cause the asphaltic substance to work its way up to the crevice, so that after a hot period the bituminous material may often work its way to the surface, while the base part will have a tendency to 80 prevent moisture from coming up, filling the crevice from below, and in this manner the entire crevice will be kept waterproof, and at the same time perform both the functions of an expansion joint and a contraction 85 joint.

In the drawing Figure 1 indicates the first form of my invention disclosing a metallic contraction joint coated on both sides with a bituminous material forming an expansion 90 joint, the opposite ends of the metallic contraction joint projecting into and being anchored into upper and lower slabs of bituminous material.

Figure 2 is a modified form wherein the 95 contraction joint of metal or other material is coated with paint or bituminous material on both sides thereof, which coating in and of itself forms the expansion joint.

Referring now to Figure 1 in detail; this 100

type of my joint is shown as comprising a contraction joint preferably formed of metal and arranged so as to provide upper and lower flanges 2 and 4 respectively, preferably 5 in the same plane, the intermediate portion of the metallic contraction joint being formed or bent to one side thereof to provide an intermediate portion which is substantially parallel with the flanged portions 2 and 4, and 10 joined to such portions 2 and 4 by inclined or wedge-shaped walls 8 and 10 respectively. This construction provides an expansion joint having a concavity on one side and a corresponding convexity on the other side, thus 15 providing an irregular cross-section serving to lock adjoining sections of the concrete and to hold them from being warped upwardly.

The ends of the flanges 2 and 4 project into slabs 12 and 14 of preferably solid bituminous 20 material, which slabs may thus form caps in which the ends of the flanges are embedded. The intermediate portions 6 and 8 of the contraction joint are covered or coated with a coating of bituminous material 16, preferably 25 on both sides thereof, which coating forms the expansion joint portion of the device.

Referring now to Figure 2. It will be noted that this form of my invention is substantially identical to Figure 1, except that the upper 80 and lower flanges are not imbedded in bituminous slabs.

In Figure 2 the metallic contraction portion is indicated by the reference numeral 18, and the coating of bituminous material by 35 reference numeral 20. Since the cross-section is similar to that shown in Figure 1 a detail reference thereto is not thought to be necessary.

It, of course, must be obvious that the metallic contraction strip 18 may either be coated 40 on one or both sides in any desired manner.

Manifestly this joint may be used as an expansion joint and laid with its upper edge flush with the concrete, or protruding there- 45 above if desired.

This application contains subject matter disclosed but not claimed in my Patent No. 1,655,835, dated January 10, 1928, which bears the filing date of January 3, 1922.

50 I claim:

1. A combined expansion and contraction joint adapted to interlock monolithic sections comprising a flexible, metallic strip having upper and lower flanged portions lying in substantially the same plane and joined by an intermediate portion lying to one side of such planes, the flanged portions being capped with bituminous slabs and the intermediate portions carrying a relatively thick coating 55 of bituminous material.

2. A combined expansion and contraction joint adapted to interlock monolithic sections comprising a flexible metallic strip having its intermediate portion bent laterally to provide a convex concave section, the upper and 60 lower edges of the strip being capped with bituminous slabs and the intermediate portion of the strip being coated with a relatively thick layer of bituminous material.

lower edges of the strip being capped with bituminous slabs and the intermediate portion of the strip being coated with a relatively thick layer of bituminous material.

3. A combined expansion and contraction joint adapted to interlock monolithic sections comprising a flexible metallic strip having upper and lower flanges lying in the same plane, the intermediate portion of the strip being bent laterally to provide an intermediate portion lying in a plane upwardly to the planes of the upper and lower flanges, and two adjoining angularly disposed portions forming inclined surfaces, the upper and lower flanges being capped with bituminous slabs and the intermediate portion of the strip carrying a relatively thick coating of bituminous material.

Signed at Chicago, Illinois, this 14th day of May 1927.

ALBERT C. FISCHER.
